UNITED STATES PATENT OFFICE.

WALTER BRANDIS, OF SAN DIEGO, CALIFORNIA.

BEET PULLING AND TOPPING MACHINE.

1,111,210.

Specification of Letters Patent. Patented Sept. 22, 1914.

Application filed December 9, 1912. Serial No. 735,778.

To all whom it may concern:

Be it known that I, WALTER BRANDIS, a citizen of the United States, residing at San Diego, in the county of San Diego and State of California, have invented certain new and useful Improvements in Beet Pulling and Topping Machines; and I do declare the following to be a full, clear, and exact description of the invention, such as will enable others skilled in the art to which it appertains to make and use the same.

This invention relates to improvements in beet pulling and topping machines.

One object of the invention is to provide a machine of this character having an improved means for pulling and conveying the beets rearwardly and holding the same in position to be engaged by the rotary knife of the machine which severs the tops at the proper place or immediately above the roots.

Another object is to provide a machine of this character which will be simple, strong and durable in construction, efficient and reliable in operation and which is provided with means for raising and lowering the forward end of the machine and for raising and lowering the plow.

With these and other objects in view, the invention consists of certain novel features of construction, and the combination and arrangement of parts as will be more fully described and claimed.

In the accompanying drawings: Figure 1 is a side view of my beet pulling and topping machine; Fig. 2 is an irregular vertical longitudinal sectional view thereof taken on the line 2—2 of Fig. 3; Fig. 3 is a plan view of the machine; Fig. 4 is a vertical cross sectional view taken on the line 4—4 of Fig. 2; Fig. 5 is a detail perspective view of one of the supporting brackets for the front operating gears of the beet pulling and conveying chains; Fig. 6 is a similar view of one of the supporting brackets of the beet guiding rods or bars of the machine; Fig. 7 is a detail vertical longitudinal section through one of the rear chain operating gears and through the rotary beet topping knife, showing the manner in which the latter is geared to and driven by said chain operating gear; Fig. 8 is a plan view of two of the links of the beet pulling and conveying chains; Fig. 9 is an

inner side view of three of the links of the chain.

My improved beet pulling and topping machine comprises a main supporting frame 1 which may be of any suitable form and which is preferably constructed in the form shown in Fig. 3 of the drawings. The frame 1 is supported at its rear end on a rear axle 2 on the ends of which are fixed rear supporting wheels 3. The forward end 65 of the frame is supported on right angularly shaped axles comprising short spindles 4 on which are revolvably mounted the front wheels 5 of the machine. On the inner ends of the spindles are formed upwardly extending standards 6 to which the forward end of the frame is slidably and adjustably secured by means of clips 7 as shown.

Bolted or otherwise secured to the front end of the frame 1 on opposite sides and adjacent to the center thereof are forwardly projecting angle brackets 8 to which are attached the beams 9 and standards 10 of beet lifting plows 11. The plows 11 are preferably in the form of longitudinally disposed inwardly inclined plates the lower edges of which are spaced a suitable distance apart whereby when the plows are drawn through the furrows on opposite sides of the rows of beets the latter will be lifted 85 from or loosened in the ground. The rear ends of the plow blades have secured thereto rearwardly projecting and converging guide rods 12 which also preferably incline upwardly toward their rear ends and which 90 guide and support the tops of the beets in position to be gripped by the pulling and conveying mechanism hereinafter described. The standards 10 of the plows are slidably attached to the brackets 8 by means of a bolt 13 which is engaged with said brackets and with curved slots 14 formed in the standards.

The inner ends of the beams and the plows are adapted to be raised and lowered 100 or adjusted, to cause the plow blades to enter the ground to a greater or less depth, by crank arms 15 formed on and projecting forwardly from a rock shaft 16 which is mounted in suitable bearings on the front 105 end of the frame 1 as shown. The outer ends of the crank arms are connected by short links 17 to the upper ends of the standards 10 and fixed on the rock shaft 16 is a hand lever 18 which projects rear- 110

wardly and carries a pawl 19 adapted to be engaged with the teeth of a segmental rack 20 secured to one side of the frame 1 as shown. By thus attaching the plow beam 5 and standards to the frame of the plow and to the rock shaft the plow beam and plows may be readily raised and lowered and supported in their adjusted positions by means of the lever 18 and its locking pawl. The 10 forward end of the frame 1 and the parts carried thereby are also adapted to be raised and lowered and to be supported in their adjusted positions by means of frame lifting levers 21 which are pivotally mounted 15 on suitable brackets 22 and are provided on their inner ends with crank arms 23. The arms 23 are connected by short links 24 with the upper ends of the standards 6 of the front wheel axles whereby when the levers 20 21 are operated in the proper direction the frames 1 may be raised and lowered at their forward ends on said standard 6 of the axle. The levers 21 are provided with suitable pawls 25 adapted to be engaged with 25 segmental racks 26 whereby the frame may be held in the position to which the same has been adjusted.

After the beets have been lifted or loosened from the ground by the plow blades 11 30 and the guide rods 12 the tops of the beets are gripped by a pulling and conveying mechanism comprising a pair of endless chains 27 which are arranged side by side and supported at a suitable angle on front 35 and rear pairs of sprocket gears 28 and 29 whereby the inner or adjacent stretches of the chains co-operate to grip and convey the beets to the rear of the machine. The front sprocket gears 28 are idle gears and are 40 revolvably mounted on bearing studs or bolts 30 secured in apertured lugs 31 on the lower ends of right angularly formed gear supporting brackets 32 which in turn are secured at their upper ends to the inner sides 45 of the front portion of the main frame 1 as shown. The rear gears 29 are preferably somewhat larger than the front gears and are revolvably mounted on stud bolts 33 secured in the forward ends of bearing brackets 34 which are secured to and project inwardly from the rear cross bar of the frame 1 as shown. On the under sides of the rear sprocket gears 29 are bevel gears 35 with the outer sides of which are operatively engaged bevel gears 36 fixed on the rear driving and supporting axle 2 of the machine. By thus supporting and driving the rear sprocket gears 29 the chains 27 will be operated in the proper direction for gripping 50 and conveying the beets from the front toward the rear end of the machine.

My improved pulling and conveying chains 27 are constructed of a series of links 37 each of which comprises upper and lower 55 parallel plates 38 one end of which is offset

inwardly and apertured to fit between the apertured opposite ends of the plates of the next adjacent link, said apertured ends of the plates being pivotally connected by rivets or bolts 39 with which the notched teeth 70 of the sprocket gears 28 and 29 are engaged when operating the chains. Secured between the plates 38 of the links are beet top gripping blocks 40 which are formed of rubber or other suitable yielding or resilient material which will firmly grip the tops of the beets when brought into engagement therewith. The bodies of the blocks 40 project beyond the links and the inner stretches of the chains are disposed at such 80 relative positions that the faces of said bodies will nearly engage and will be brought close enough together to grip the tops of the beets caught between the chains. The bodies of the blocks 40 are of greater 85 length than the link engaging portions thereof and on the inner stretches of the chains the ends of the adjoining bodies will engage one another as shown. The blocks in the links when passing around the 90 sprocket gears with which they are engaged separate slightly and provide spaces which receive the leaves of the beet tops as the blocks are brought around the inner sides of the front gears 28, so that when the ends of 95 the blocks come together on the inner stretches of the chain the leaves between said ends are firmly gripped and pulled out of the ground and from between the guide rods of the plow blades. Any of the leaves of 100 the tops which are not gripped between the ends of the blocks 40 will be caught between the faces of the blocks when they come together on the inner stretches of the chain, thus firmly holding the beets while they are 105 being conveyed rearwardly by the chains.

Revolvably mounted in one of the supporting brackets 34 of the rear gears 29 is a rotary beet topping knife 41 comprising a series of radially projecting blades 42 110 which are adapted to be brought into engagement with the tops of the beets as the latter are carried upwardly and rearwardly by the conveyer chains 27. The knife 41 is operated by a gear pinion 43 fixed on the 115 upper end of the shaft of the knife, said pinion engaging an annular series of internal gear teeth 44 formed on the inner side of a depending flange on the gear 29 as clearly shown in Fig. 7 of the drawings. 120

In order to draw the beets downwardly between the conveying chains and to hold the beets in such position when brought into engagement with the blades of the knife that the top will be severed immediately 125 above the root, I provide a beet guiding and adjusting mechanism comprising a pair of suitably spaced rods or bars 45 which are disposed below the inner stretches of the chains 27 and are supported at their for- 130

ward ends by depending angular brackets 46 secured at their upper ends to the side bars of the main frame 1. The rear ends of the bars or rods 45 are extended and secured to the rear cross bar of the frame 1 in any suitable manner. The space between the rods or bars 45 and the inner stretches of the chains 27 gradually increases from the forward ends toward the rear ends of 10 said bars and the forward ends of the bars turn outwardly to a slight extent to receive the beets when brought up by the conveyer chains, said rods engaging the beet top immediately above the root and, owing to the 15 increase of the space between the rods and the chains, the beet is gradually pulled downwardly by the rods so that when the beet reaches a position to be engaged by the blades of the rotary knife, the top will 20 be severed adjacent to or immediately above the root as is clearly indicated in Fig. 2 of the drawings.

From the foregoing description taken in connection with the accompanying drawings, the construction and operation of the invention will be readily understood without requiring a more extended explanation.

Various changes in the form, proportion and the minor details of construction may 30 be resorted to without departing from the principle or sacrificing any of the advantages of the invention as claimed.

Having thus described my invention, what I claim is:

35 1. In a beet pulling and topping machine, a wheeled supporting frame, beet lifting plows connected therewith, beet pulling and conveying chains comprising links each of which consists of pairs of parallel plates

offset inwardly at one end to fit between the 40 ends of the plates of the next adjacent link, said ends having alined apertures, rivets connecting the apertures, resilient beet top gripping blocks secured between the plates of said links and projecting therefrom 45 whereby the inner faces of said blocks are adapted to coact on the inner stretches of the chains to grip the tops of the beets, a rotary knife in said frame, and means to adjust and hold the beets in such position 50 that the tops will be severed by the knife immediately above the roots of the beets.

2. In a beet pulling machine, the combination with the wheeled frame, the digging mechanism, and two pairs of gears mounted 55 on the frame; of two endless chains whereof each embraces one pair of gears, the latter being so disposed that the inner stretches of the chains lie parallel close to each other and incline upward and rearward, each 60 chain comprising links consisting of spaced plates riveted in pairs to the plates of the adjacent link, and rubber gripping blocks whose bodies lie outside the line of said plate and on the outer side of the chain so 65 that their working faces on the inner stretches of said chain come nearly into contact with each other, the outer portions of said bodies being of reduced length and secured between the plates of the links re- 70 spectively.

In testimony whereof I have hereunto set my hand in presence of two subscribing witnesses.

WALTER BRANDIS.
